(57) **CLAIM**

The ornamental design for an oil container, as shown and described.

DESCRIPTION

FIG. 1 is a perspective view of an oil container, showing my new design;

FIG. 2 is a front view thereof;

FIG. 3 is a back view thereof;

FIG. 4 is a side view thereof, shown in an enlarged scale;

FIG. 5 is an opposite side view thereof, shown in an enlarged scale;

FIG. 6 is a top view thereof; and,

FIG. 7 is a bottom view thereof.

The broken lines in the figures show portions of the oil container that are not part of the claimed design.
